UNITED STATES PATENT OFFICE.

CHARLES W. SPONSEL, OF HARTFORD, CONNECTICUT, ASSIGNOR OF ONE-HALF TO CHARLES F. TAYLOR, OF HARTFORD, CONNECTICUT.

MACHINE FOR INSPECTING NAILS.

SPECIFICATION forming part of Letters Patent No. 766,200, dated August 2, 1904.

Application filed September 25, 1903. Serial No. 174,577. (No model.)

To all whom it may concern:

Be it known that I, CHARLES W. SPONSEL, a citizen of the United States, residing at Hartford, in the county of Hartford and State of Connecticut, have invented certain new and useful Improvements in Machines for Inspecting Nails, of which the following is a specification.

My invention relates to machines for selecting and presenting nails for inspection, especially those of the horseshoe variety. Heretofore these nails have been deposited in masses on a table and have been selected one by one by an operator who inspects or is supposed to inspect each nail on its two sides, its two edges, and the point and head, rejecting those that are impaired in any way and selecting the perfect ones for package and sale. These operations are slow and tedious and, due to the haste of the operator to accomplish the required task, frequently result in the selection of imperfect products detrimental to the perfection of the brand, and therefore often causing a decrease in demand, and consequently of the number manufactured. Furthermore, as each nail is handled by the operator, deposits of perspiration on the metal are liable to and do occur, thereby causing oxidation and frequently a rejection of the product.

Primarily the object of my invention is the provision of a machine for selecting and inspecting nails in which all operations are carried out mechanically without handling in any way and in which nails not of standard size and not of perfect form will be withdrawn and rejected for trade purposes.

A further object of the invention is the provision of means, broadly, for mechanically selecting nails and for presenting them for inspection either at all points of their super- 40 faces or at any points thereof which may be required, the selecting and presenting operations being carried out rapidly as compared with the old hand method and resulting in a great saving of time and labor and of expense in wages.

A further object of the invention is the provision of a carrier for presenting the nails for

inspection and of means for actuating said carrier.

A further object of the invention is the provision of means for turning the nails presented by the carrier to the positions required for inspection.

Other objects of the invention will be set forth in the description hereinafter given.

In the accompanying drawings, Figure 1 is a plan view of the improved machine for selecting and presenting nails for inspection, the hopper being removed and parts being shown in section. Fig. 2 is an end view of said machine. Fig. 3 is a side elevation. Fig. 4 is a section on line *xx* of Fig. 1 looking in the direction of the arrow. Fig. 5 is a view, 60 partially in section and partially in elevation, of the nail-carrier. Fig. 6 is a horizontal section of said nail-carrier, showing the coil of the electromagnets in plan. Fig. 7 is a transverse section on line *rr* of Fig. 6. Fig. 8 is a 70 transverse section on line *mm* of Fig. 6. Fig. 9 is a transverse section on line *zz* of Fig. 6. Fig. 10 represents the carrier in position to present the heads of the nails for inspection. Fig. 11 represents the carrier with the nails 75 in position to present one of their edges for inspection. Fig. 12 represents said carrier with the nails turned thereon to present their upper sides and points for inspection. Fig. 13 is a view similar to Fig. 11 with the nails 80 turned to present their opposite edges for inspection. Fig. 14 represents the carrier with the nails turned to present their backs for inspection. Fig. 15 is a view representing the carrier turned to a position to inspect the 85 points and discharge the nails. Fig. 16 is a synchronized diagram of the main cam-drum, showing the cams thereof developed. Fig. 17 is a detail view of the upper set of inclined feed-rolls, showing part of the gearing for 90 driving the screw conveyers. Fig. 18 is a detail view, partially in section, taken on about line *aa* of Fig. 17. Fig. 19 is a section on line *bb* of Fig. 18, showing the slotted back of the feed-chute between the feed-rolls and 95 the screw conveyers. Fig. 20 is a side view of part of the machine, illustrating the relative locations of the feed-rolls, intervening

chute, and screw conveyers. Fig. 21 is a longitudinal section of one of the chucks, the spindle thereof being in elevation. Fig. 22 is an end view of one of said chucks. Fig. 23 is 5 a detail view, partially in section and partially in elevation, of a circuit establishing and breaking device. Fig. 24 is an end view of the device represented in Fig. 23. Fig. 25 is a partial section on line *c c* of Fig. 1. Fig. 10 26 is a transverse sectional view showing the carrier and its supporting-arms swung to a position where the magnets of said carrier will attract the set of nails to be inspected from the conveyer-screws. Fig. 27 is a view 15 similar to Fig. 26, showing the carrier in position for the head inspection of the nails. Fig. 28 is a similar view representing the carrier rocked ninety degrees to present the nails for the first edge inspection and also shows by 20 dotted lines one of the chucks for turning the nails from flat to edge positions, and Fig. 29 is a similar view representing the carrier rocked another ninety degrees or to the point inspecting and discharging position.

25 Like characters designate similar parts throughout the several views.

Referring to the drawings, the numeral 10 designates in a general way the frame of the machine, which may be of any form suitable 30 for the purpose, is supported by legs or standards 11, and has a top 12. Journaled in a bearing 13 of the frame is a sleeve 14, carrying at its outer end a clutch-section 15, shown as of the friction type, and loosely mounted 35 on the bearing 13 is a driving-pulley 16, having a complementary clutch-surface 17. Any suitable clutch-surfaces may be employed as substitutes for those shown and other driving elements may be used in lieu of pulley 16 40 without departure from the invention. At its inner end sleeve 14 is provided with a grooved collar 14' for the reception of pins or shoes projecting from a fork 18, carried by an angle-lever 19, pivoted at 20 to a bracket 45 of the frame and having a bifurcated arm 19', in which is fitted a pin 21. For actuating 45 this lever 19 to throw the clutch into and out of action any desired means may be employed, that shown being a treadle 22, pivoted at 23 50 to one of the legs 11 of the frame and connected by a link 24 with said lever, the link being slotted at 24' to have a limited play upon pin 21 for a purpose hereinafter stated.

55 Mounted within the sleeve 14 is a driving-shaft 25, having a slot 26 in its outer end, through which passes a pin 27 for connecting the hub of the clutch-section 15 to said shaft, said slot being of sufficient width to permit play of the pin when the clutch-section is 60 thrown into and out of connection with the complementary clutch-surface 17 of pulley 16. Shaft 25 is also journaled in bearings 28 of a hanger 29 and carries between said bearings a worm 30, in engagement with a worm-wheel 31, secured to a shaft 32, and on this shaft is

fixed a cam-drum, (designated in a general way by 33,) the cams of said drum actuating many of the principal parts of the machine, as will be hereinafter described.

Designated by 34 is a hopper into which 70 the nails are thrown in mass, and this hopper is provided on its under side with a bracket 35, carrying a hub 36, mounted on a pivot 37, connecting the arms of a fork 38. To enable the hopper to be adjusted to the proper 75 angle, a web or ridge 35' of the bracket is provided with a series of holes 39, through which a pin 40 may be passed, as illustrated in Figs. 3 and 4, and by removing this pin, then swinging the hopper, and again securing 80 the pin the desired position of said hopper may be obtained. Other means for accomplishing this result may be employed as substitutes for those shown without departure 85 from the invention.

To cause the nails to slide by gravity along the bottom of the hopper, said hopper must be shaken to agitate the mass, and while any desired means may be employed for accomplishing this result the following arrangement is preferred: Fork 38 is provided with a hub 38', which is keyed at 41 to a vertical shaft 42. Loosely surrounding this shaft is a sleeve 43, which is adjustably secured in a bearing 44 by screws 46, said bearing projecting from an arched bracket 45 rising from the frame. Designated by 47 is an antifriction or ball-bearing washer surrounding the vertical shaft 42 and placed between the lower end of the hub 38' and the flanged top 90 of sleeve 43, the rotary top plate of said washer receiving the weight of the superimposed hopper and its contents. To the lower end of shaft 42 is secured by a screw 48 an arm 49, carrying at its free end an anti-friction-roller 50, and on the cam-drum is an undulatory cam 51, having a series of cam-surfaces 52, against which the roller 50 of arm 49 is held by a spring 53, secured at one end to the arm and at its opposite extremity 100 to the arched bracket 45, as shown in Fig. 1.

From what has been stated it is obvious that the hopper 34 will be continuously vibrated while the machine is in action, thereby shaking the mass of nails and causing them to slide one by one into the hopper-spout 34', from which they drop into the pockets of a drum-wheel 54, about to be described, said drum-wheel being disposed at an angle with relation to the frame, as shown in Fig. 3. 115 This drum-wheel is formed of side plates 55, united by hollow diamond-shaped cross-bars 56, so located with relation to each other that a flaring nail-receiving pocket 57 is formed between two opposing sides of the said bars 120 and a channel 58 between the other parts of the bars, said channel being of a width but slightly in excess of the standard thickness of the head of a horseshoe-nail.

125 Rising from the top 12 is a standard 59, 130

having an opening for the reception of a tubular hub 54' of said drum-wheel, and on this hub outside of the standard is secured a ratchet-wheel 60, actuated to rotate the drum-wheel intermittently by means hereinafter described.

Designated by 61 is a standard in which is mounted a vertical shaft 62, carrying at its upper end a bevel-gear 63 and at its lower extremity a bevel-gear 64, said gear 64 being in mesh with a like gear 65, fixed on the driving-shaft 25 by a screw 66, passing through its hub, and the latter carrying an eccentric 67.

In a bracket 68 of standard 61 are journaled the ends of two inclined feed-rolls 69 and 70, connected to rotate in opposite directions by gears 71 and 72, and secured to the end of roll 69 exterior to the bearing in bracket 68 is a bevel-gear 73, in mesh with the gear 63 of vertical shaft 62. As shown in Figs. 1, 2, 3, and 4, these inclined feed-rolls pass through the hub of the drum-wheel 54, and they are separated a distance apart equal to the thickness of the shank of the nail, as shown more clearly in Fig. 4.

Designated by 74 is a standard having an offset inclined bearing-bracket 75 at its upper end for the reception of the lower journals of the feed-rolls just described, and roll 70 is provided adjacent to said bearing-bracket with a screw-section 76 for engaging and feeding the nails, which hanging by their heads between the feed-rolls have slid by gravity, aided by the rotation of said rolls, to this point.

For intermittently rotating the ratchet-wheel 60, secured to the hub of the drum-wheel 54, any desired means may be employed; but there is shown for this purpose an angle-lever 77, pivoted at 77' to the stand 59, one arm of said lever carrying a spring-actuated pawl 78 and the other arm being connected to a link 79, in turn articulated to a crank-arm 80, attached to a shaft 81. Loose on said shaft 81 is a gear 82, carrying a ratchet-wheel 82', and rigid with the shaft below the arm 80 is a crank-arm 83, articulated to a pitman 84. Also rigid with shaft 81 is an arm 85, carrying a pivoted pawl 85', in engagement with ratchet-wheel 82', the latter being fixed to gear 82 by a pin 86. Shaft 81 is journaled in a bearing 87, formed in a bracket 88, said bracket extending across the frame and having an angular extension 88', as shown in Figs. 1, 18, and 20. When the eccentric 67 is in motion, the pitman 84 will turn the shaft 81, and the pawl 85' of arm 85 will engage the ratchet-wheel 82' and intermittently rotate gear 82, said shaft 81 through crank-arm 80, link 79, angle-lever 77, and pawl 78 synchronously actuating the ratchet-wheel 60 and its connected drum 54.

Intermediate the points in bearing-bracket 75, where the lower ends of feed-rolls 69 70 are journaled, is a slot 75', and communicat-

ing with this slot is a chute 89, the passage-way of which is of area sufficient to receive freely the head of a nail, and in its rear wall this chute has a narrow slot 89' of dimensions sufficient to receive the point and shank of the nail, but to stop the passage of its head, so that should the nail turn as it passes from the feed-rolls 69 70 its head cannot escape through said slot. This slot is of the same width as the space between the feed-rolls, and the shanks of the nails pass therethrough on their way to the chute 89, as shown in Fig. 18.

Mounted on a stud 90, Fig. 18, projecting from extension 88' of bracket 88, is a gear composed of a small pinion 91, in mesh with wheel 82, and a larger pinion 92.

Journalized in the end extensions 88' of bracket 88 are the shafts of two screw conveyers 93 and 94, located one above the other below the chute on a line diagonally crossing the bracket 88 and spaced a considerable distance apart, as shown in Fig. 18, and for rotating said conveyers in the same direction each conveyor-shaft is equipped with a pinion 95 and 96, respectively, both of which are driven in the same direction by the pinion 92, as shown in Figs. 3 and 18, when said pinion is intermittently actuated in the way above described.

As thus far set forth it will be seen that the nails as they drop from the spout 34' are received in the pockets 57 of the intermittently-rotating drum-wheel 54, and here it may be stated that no matter in what position the nail enters the passage-way 58 it will under the action of gravity always right itself so that it will hang by the head between the feed-rolls 69 and 70. As said rolls are inclined and are constantly rotated, the suspended nails slide along between them until a column is formed, the lower members of said column being positively engaged by the screw 76 and fed one by one until a nail leaves the feed-rolls and enters the slot 75', through which it will drop into the chute 89, passing on edge through said chute and entering the grooves between two threads of the then stationary screw conveyers 93 and 94, as illustrated in Fig. 18.

Designated by 97 is a light spring, beneath which each nail passes as it leaves the chute and engages the screw conveyers, the object of said spring being to retard the velocity of the falling nail and prevent injury to its point when it strikes a stop-plate 98, extending across the machine, said stop-plate having flanges 98' secured to the ends of the bracket 88 and also having a longitudinal lip or projection 98" for preventing upward movement of the nails, due to the rotation of the screw conveyers in the same direction. It will be seen that as the nail falls with accelerated velocity through the chute such velocity will be retarded by the spring 97, which bears upon

the edge of the nail so that its point will strike the stop-plate lightly and will not be injured by contact therewith, as above stated.

In the "timing" of the machine the screw 5 conveyers will, as stated, be at rest when a nail falls edgewise into two of their alined grooves, as shown in Fig. 18, and said conveyers will then be rotated a step to advance the nail first received, will then be stopped to 10 receive another nail, will then again be rotated, and so on until the desired number of nails is carried by them, when said nails will be taken from the conveyers by a carrier about to be described and will be presented 15 by said carrier for the several inspections.

Preferably a magnetic carrier is employed, although the invention is not limited to one of this type, and a form of such carrier which may be used is illustrated in Figs. 5 to 9, inclusive, and is shown in its various positions in Figs. 10 to 15 and 26 to 29, inclusive. This carrier is designated by 99 and is of hollow rectangular form.

Two plates 100, of brass or other non-magnetic material, each having notches 100' for the reception of nails, constitute the sides of the carrier, and back of these plates are iron or other magnetizable plates 101 of less width than the plates 100, so that their upper edges 25 will be below the bases of the notches 100' and will therefore not come into contact with the nails, said plates being separated to form a coil-receiving chamber by a central core 102, around which is placed an oblong coil 30 103, composed of insulated wire of fine gage. To inclose and protect the coil, top and bottom plates 104, of brass or other non-magnetic material, are placed between the plates 101 and all the parts are firmly secured together 35 by screws 105 passing through the side plates and threaded into the core, as shown in Figs. 5 and 9. Trunnions 106 have heads 107 for closing the ends of the coil-chamber, and these heads are grooved at 107' to receive rabbets 40 104' on the protecting-plates 104 and have flattened sides 107", upon which the ends of the plates 101 rest, screws 108 passing through said ends and entering nuts in the heads. Spools 109, composed of vulcanized fiber or 45 other insulating material, surround and are keyed to the trunnions 106, and the flanges of said spools bear on one side against collars 110 of the arms 113 113' and on their other sides against the heads 107. Between the 50 flanges of each spool is a metallic contact-ring 111 111', respectively, and the ends 103' 103" of the coil, from which the insulating material has been stripped, are inserted in said contact-rings, as shown in Fig. 6. Reduced extensions 106' 106" of the trunnions are 55 journaled in bearings 112 112' of arms 113 113', and in the top of the bearing of arm 113 is formed a chamber 114 for the reception of a plunger 115, in a bore of which is inserted 60 a spring 116, the tension of which may be reg- 65

ulated by a screw 117, threaded into the bore, as shown in Figs. 5 and 7, trunnion extension 106' being provided with three flattened portions 106", against which the plunger bears, said plunger serving to secure the carrier 99 70 against movement during the several inspecting periods hereinafter described. To a reduced end of extension 106' is keyed a gear-wheel 118, held against longitudinal movement by a nut 119, said gear-wheel being actuated by means hereinafter described. 75

Designated by 120 is a stand, in bearings 120' of which is journaled a shaft 121, to which the arms 113 113' are secured, and attached to the end of this shaft adjacent to arm 113' 80 is a crank-arm 122, to the free end of which is articulated a connecting-rod 123, whose opposite end is pivoted to a rocker 124, mounted on a stud 125 of the frame, as shown in Fig. 3, the lower end of said rocker, which is a lever of the first order, having a stud and roller 126 fitted in the groove 127 of main cam 33, said groove having reversely-inclined active portions 128 129 for quickly raising and lowering the arms 113 113' to cause the carrier 85 to approach the screw conveyers 93 and 94, receive its load from said conveyers, and to return to its normal position, as illustrated in Fig. 27.

To energize and deenergize the plates 101 90 of the carrier at the proper times, a contact device is employed, and although various means are applicable for accomplishing this result I prefer to use an angle-lever 131, pivoted at 130 to a stand 132 on the top of the machine, said stand being separated from the top by a bed 133, of insulating material. One arm 131' of the angle-lever is chambered and is packed with insulating material 135, and surrounded by this material is a contact-rod 136. Binding-posts 137 137' in the form of screws serve to secure the flanged bases of contact-strips 138 138' to said insulating-bed, (said strips being bent, as shown in Fig. 24, to form parallel rod-engaging surfaces 138") 100 and a wire 139 is secured by the screw 137 to the base of the contact-strip 138' and passes therefrom through an opening of the frame top to one pole of a battery 140 or other source of electric energy, while a conductor 141 is 105 secured by a post 137 to the base of contact-strip 138, passes through openings of the top, and is secured by a binding-post 142 to a curved metallic plate 143', mounted on a ring 110 of insulating material 144', surrounding and secured to a stud projecting from one of the shaft-bearings 120' of stand 120. Inwardly projecting from arm 113' is a block 145', of insulating material, to which is secured a contact-strip 146', one end of said strip bearing 115 upon the contact-ring 111' of carrier 99 and the opposite extremity upon the curved contact-strip 143', as shown in Figs. 1 and 26 to 120 29, inclusive. Leading from the opposite pole of the source of energy 140 is a wire 147, 125 130

passing under and through the machine-top and secured to a curved contact-strip 143, insulated in a like manner to that of strip 143' from the stand 120, and attached to an insulating-block 145, projecting from arm 113, is a contact-strip 146, having its ends in engagement with the contact-ring 111 and curved contact-strip 143. Journaled on a stud of arm 131² of lever 131 is a roller 148, which bears upon the periphery of cam 149 of the main cam-cylinder 33, said cam having inclined portions 149¹ 149², connected by a flat part 149³, as shown in Fig. 16. From what has been stated it will be evident when the roller 148 is raised by cam 149 the contact-rod 136 will be thrown temporarily from a point between the parallel parts 138¹ of contacts 138 138² to the position represented in Figs. 23 and 24, where it will be out of engagement with the contact-strips, and the circuit leading to the electromagnets 101 of carrier 99 will be broken until the roller passes off from the incline 149³ of the cam, when a spring 150 will immediately act to throw the lever-arm 131 downward to carry the roller into contact with the plain portion of the cam and to throw arm 131' and its contact-rod 136 upward, the latter pressing apart and reengaging the contact-strips 138 138², thus establishing the circuit and again energizing the plates 101 of the carrier.

Here it may be stated that the circuit to the magnets is established during all of the inspecting periods of the nails and that in the timing of the machine when the last inspection has been made the cam 149 will have arrived at a point to actuate the lever 130 and break the circuit, thereby deenergizing the magnets and permitting the inspected nails to drop from the carrier.

For rocking the carrier a toothed sector 151 in engagement with gear 118 is provided, said sector being at the end of an arm 151', having a hub 151² sleeved loosely upon the shaft 121 between an end collar 152 thereof and the hub of arm 113, and for actuating said sector a rod 153 is articulated to a projection of arm 151' at one end and extending across the machine is connected to the upper end of a rocker 154, pivoted intermediate its length to a hanger 155, depending from the machine-top, as shown by dotted lines in Figs. 2 and 3. At its lower end this rocker is provided with a stud and roller 156, entering a groove 157 of the main cam-cylinder 33. This cam-groove is shown developed in Fig. 16 and has a straight portion *a*, a short inclined or active portion *b*, a long straight inactive portion *c*, a second short inclined portion *d*, a following straight part *e*, an incline *f*, an opposite incline *g*, and another incline *h* for purposes hereinafter set forth.

Designated by 158 is a stand having ways for the reception of a slide 159, which is located opposite the carrier when the latter is

in its normal position. This slide is grooved at 159' for the reception of a rack 160, said rack having a slotted projection 160' at its end to receive a pin 161 on one arm of a horizontally-pivoted angle-lever 162, the other arm of said angle-lever carrying a stud and roller 163, bearing against a cam-surface 164 of the main cam and being held against said surface by a spring 165, as shown in Fig. 1. This cam-surface has a long straight portion 75 *i*, is inclined to the right at *j*, straight at *k*, inclined to the right at *l*, has a short straight portion *m* at its rise, is inclined to the left at *n*, has a short straight portion *o*, terminating in a right incline *p*, followed by a flat top *q* 80 at the rise, and an incline to the left at *r*, said incline *r* merging into the long straight part *i*, as shown in Fig. 16 and for purposes hereinafter stated.

Connected to a tongue of the slide 159 is a 85 link 166, articulated at its rear end to a lever 167, pivoted at 168 to a standard 169, secured to the top of the machine. A pin 167' at the end of lever 167 has a roller fitted in a groove 170 of the main cam, said groove being composed of a long straight inactive portion *s*, a right incline *t*, a short straight part *u*, a left incline *v*, a short straight part *w*, another like portion *t' u' v'*, a short straight part *w* and still another like inclined and straight section *t' u' v'* 95 *w*, and by this cam the slide is actuated in proper timing with other coöperating parts, as will hereinafter appear. Journaled in the slide are spindles 171, each carrying a pinion 172 at its rear end, and pinned to each spindle 100 is a chuck 173, having a cup-shaped flaring front end 173¹, a rectangular slot 173² for the reception of the shank of the nail, and a chamber 173³ back of the slot. These chucks advance upon the shanks of the nails held by 105 the carrier 99, and to prevent said nails from being displaced longitudinally of the carrier arms 174 174' are secured to the stationary bearings 120' of stand 120, said arms carrying an abutment-bar 175 for preventing movement of the nails when the chucks engage them, as shown in Figs. 1, 26, 27, 28, and 29. As the nails may wobble slightly when received by the chucks, each chamber 173³ will afford space for this action.

Carried on the end of the main shaft 32 is a wheel 176, having its periphery cut away to produce a series of stops 1, 2, 3, 4, 5, and 6, hereinafter described.

Pivoted intermediate its length to a hanger 120 177 is a lever 178, and articulated to the long arm of this lever is a rod 179, having a fork 180, connected to the treadle-lever 22. At its inner end lever 178 carries a pivoted bypass 181, held normally against a stop 182 by 125 a spring 183, and said lever is held in the position illustrated in Fig. 1 by a spring 184, said spring serving also as a means for throwing the clutch into action through the parts intermediate the lever 178 and the clutch- 130

sleeve 14, as above described and as illustrated in Figs. 1 and 4.

To insure the selection of perfect work, each nail must be inspected at six different points, viz: first, the head, Fig. 10; second, one edge, Fig. 11; third, the front and beveled point, Fig. 12; fourth, the opposite edge, Fig. 13; fifth, the back, Fig. 14, and, sixth, the end of the point, Fig. 15, for if found defective in any of these particulars it will not be up to standard and must be rejected.

A seat for the operator (who looks down upon the carrier) is placed in front of the stand 120, and as the nails are subjected to visual inspection, aided, if necessary, by a magnifying-glass, the carrier must be held stationary for a sufficient period to enable each inspection to be made, and if a nail is found defective it is picked off from said carrier by hand and discarded, the plates or electromagnets 101 not being of sufficient power to interfere with such action.

Normally the clutch-sections 15 and 17 are in engagement; being so maintained by the spring 184 acting upon the clutch-sleeve 14 through the medium of the lever 178, rod 179, treadle 22, slotted link 24, and angle-lever 19, and to start the machine power is applied to pulley 16 by means of a belt leading from the usual counter-shaft. As shown in Fig. 27, the shaft 121 has been rocked by cam-groove 127 and the connections from roller 126 described to bring the arms 113 113' to the position for the first or head inspection, where said arms remain during all of the subsequent inspecting periods. (See Figs. 28 and 29.) At this period and the other inspecting periods the roller 148 controlling contact-rod 136 is upon the long plain part of cam 149, the sector-controlling roller 156 is in the plain part of groove 157, it having just left the incline *b* of said groove, the arm-controlling roller 126 is in the plain part of cam-groove 127, the slide-controlling roller 167' is in the straight parts of cam-groove 170, and the rack-controlling roller 163 is on the straight part *i* of cam 164, all as indicated by the dotted line 0 in Fig. 16, and the nails of the carrier are in position for the second or edge inspection thereof, as shown in Fig. 11.

At the termination of the second inspection period the nails must be given a quarter-turn to present their fronts for inspection, and this is accomplished by the chucks 173, whose slide 159 is then driven forward by the part *t* of cam-groove 170 in engagement at this time with the roller 167', as shown in Fig. 16, to cause the chucks to engage the nail-shanks, the rack 160 being then operated by incline *j* of cam 164, which acts upon the roller 163 of angle-lever 162, thereby rocking said lever, shifting said rack toward the right, and imparting a turning movement of ninety degrees to the nails, or, in other words, turning 65 them from the edge position (shown in Fig.

11) to the face or front position (illustrated in Fig. 12) in readiness for inspection No. 3. At the inception of this inspection period the slide 159 is withdrawn by the incline *V* of cam-groove 167' and is held in such withdrawn position by the short straight part *w* of said groove, and the rack-controlling roller 163 is forced by spring 165 against the short straight part *l* of cam 164 and holds the rack 160 in its shifted position during the entire third inspection period, and at the conclusion of said period slide 159 is again advanced by the second incline *t'* of groove 170 and is held momentarily by short straight part *u'*. Roller 163 is again advanced by incline *l* to impart a further movement to the rack toward the right, thereby turning the spindles and their chucks 173 another ninety degrees and bringing the nails from the position shown in Fig. 12 to the opposite edge position (represented by Fig. 13) in readiness for the fourth inspection period. After a short dwell, due to the straight portions *m* and *u'*, the rack and slide are immediately withdrawn by inclines *n* and *v'* and are maintained in their withdrawn positions during the fourth inspection period. During this period the nails rest on their edges in the notches 100' of plates 100, as represented in Fig. 13, and at the termination thereof the slide is again advanced by the third incline *t''* of cam 170 to force the chucks upon their shanks, and the rack-controlling roller 163 engages the cam *p*, thereby again shifting the rack to the right and rotating the chuck-spindles another ninety degrees to turn the nails from the position represented in Fig. 13 to that illustrated in Fig. 14, (the fifth inspection period,) where their backs are presented for inspection, after which the incline *v''* withdraws the slide, and the spring 165 rocks lever 162, forces the roller 163 against incline *r*, and returns the rack to the left to its normal position. After said fifth inspection period roller 167' travels in the straight inactive part *s* of cam-groove 170, and the slide 159 is held stationary until the inspection of the lot held by the carrier is completed and the carrier has been rotated to the position illustrated in Figs. 15 and 29.

To present the nails for the sixth or final point inspection, the carrier 99 must be turned ninety degrees, or from the position represented in Fig. 14 to that illustrated in Figs. 15 and 29, and this is accomplished by the sector 151, in mesh with the pinion 118 on the trunnion 106 106' of said carrier.

As before stated, the arm 151' of sector 151 is connected by rod 153 with a rocker 154, having a stud and roller 156, working in the cam-groove 157 of cam 33, and said roller 156 has thus far followed the straight part *c* of the cam-groove, as shown in Fig. 16. Now, however, said roller enters the inclined part *d* of the groove, thereby actuating, through the parts described, the sector 151, 130

and thus turning the carrier to the position illustrated in Figs. 15 and 29, where the points of the nails are presented vertically for the sixth inspection period, the carrier being held during this period by the engagement of the roller 156 with the straight part *e* of said groove 157.

During all of the movements of the carrier thus far described the roller 148 of lever 131 has been held against the straight inactive part of cam 149, as shown in Fig. 16; but at the end of the final inspection period said roller is forced upward by the incline 149', thereby rocking the contact-rod 136 to the position illustrated in Figs. 23 and 24, breaking the circuit, deenergizing the plates 101, and permitting the inspected nails to fall from the carrier. If the nails were in direct contact with plates 101, the effect of residual magnetism in said plates after the circuit is broken might prevent their free discharge, and to overcome this difficulty the nails are supported above said plates, but within the magnetic field, in the notches 100' of the brass or other non-magnetic plates 100, said notches being of sufficient width to enable the nails to be freely turned therein to the positions above described. Other means for preventing the effects of residual magnetism may be employed, if desired, the invention not being limited in this respect. During the short time that the circuit is broken the roller 148 engages the straight part 149' of cam 149, and as cam 33 moves onward it then rides down the incline 149', permitting the spring 150 to rock lever 131, and thus throw the contact-rod 136 between the parallel parts 138' of contact-strips 138 138' to reestablish the circuit and again energize the plates 101.

After an inspected lot of nails has been discharged the shaft 121 is actuated to throw the arms 113 113' and carrier 99 downward to the position represented by Fig. 26, and this is accomplished by connecting-rod 123, rocker 124, and cam-groove 127 engaging the roller 126 of said rocker in the following manner: Referring to the diagram, it will be seen that after leaving the long inactive part of said cam-groove the roller 126 enters incline 128 of said groove and is actuated thereby to throw the carrier, through the connections described, from the position shown in Figs. 15 and 29 to that illustrated in Fig. 26, where a new lot of nails is taken from the screw conveyers 93 and 94 by the electromagnets 101; but before this is accomplished the carrier must be turned one hundred and eighty degrees, or from the position represented in Fig. 29 to that shown in Fig. 26, and this is done by the incline *f* of cam-groove 157, which acting upon roller 156 actuates, through described connections, the sector-arm 151', thus turning the hub 151' of said arm upon shaft 121 and, through the intermeshing sector 151 and pinion 118, rotating said carrier to the re-

quired position, or that represented in Fig. 26. As the carrier under the action of incline 128 swings downward to obtain a new supply of nails the sector 151 must move with it and without turning said carrier, and, as will be seen by referring to the diagram, the roller 156, controlling the sector, enters an incline *g* of groove 157 simultaneously with the entrance of roller 126 into the incline 128 of groove 127, thereby imparting simultaneous movements to the sector and carrier-arms and of course not rotating the carrier. After a new lot of nails has been received by the carrier it must be returned to the first or head-inspecting position (shown in Fig. 27) without being rotated by the sector 151, and this is done by the inclined section 129 of cam-groove 127, the section *h* of cam-groove 157 at this time engaging roller 156 and causing the sector-arm 151' to rotate with shaft 121 in synchronism with the movement of the carrier-arms 113 113'.

By inspection of the diagram it will be seen that the cam 33 travels from the dotted line 1 to the line 2 during the first or head inspection period without actuating the carrier; that the sector 151 is then actuated by roller 156 working in incline *b* of cam 157 to turn the carrier to the position represented in Fig. 11 for the second inspection period when the cam travels from line 2 to line 0; that between the line 0 and line 3 said second inspection period takes place; that between lines 3 and 4 the first incline *t* of cam-groove 170 will actuate the roller 167' and force the slide 159 forward to cause the chucks 173 to engage the nails; that immediately thereafter during the travel of the cam from line 4 to line 5 the rack-controlling roller is actuated by incline *j* of cam 164 to cause the chucks 173 to be rotated to turn the nails from the edge positions to the face presentation represented by Fig. 12 for the third inspection period, the rack being held stationary during this period by the raised plain part *k* of said cam 164 as it travels from about line 5 to line 7; that as cam 33 rotates from line 5 to line 6 the incline *r* will cause roller 167' and connections to withdraw slide 159 and its rack 160 to normal position and hold it there until the roller 167' leaves section *w* of cam-groove 170 at line 7 and enters the second incline *t'* to be forced forward, held at *u'*, and returned at *v'* between lines 7 and 10 to cause the chucks to engage the nails and to be again rotated ninety degrees by the rack 160, whose controlling-roller 163 is forced forward by incline *l*, held momentarily by short straight section *m* between lines 9 and 10 and then withdrawn as it passes along incline *n* between lines 10 and 11, the slide 159 having been previously withdrawn by the action of incline *v'* as the cam travels from line 9 to line 10; that by this action of the parts the nails have been turned from their face positions, Fig. 12, to the opposite edge positions, Fig. 13.

Fig. 13, where they are maintained for the fourth or opposite edge inspection as the roller 163 travels along straight part *o* of cam 164 between lines 11 and 13 and while the straight part *o* of cam-groove 170 engages the roller 167' between lines 10 and 12; that after the fourth inspection has been made roller 167' will enter the incline *t*² between lines 12 and 13, which will again force slide 159 forward, 50 roller 163 then being engaged by incline *p* of cam 164 between lines 13 and 14 to actuate the rack 160 and turn the chuck-spindles ninety degrees, and thus present the backs of the nails for the fifth inspection period, as illustrated in Fig. 14; that the slide and rack are then withdrawn by inclines *v*² and *r* between lines 14 and 15 and 15 and 16, respectively; that cam 33 travels from line 16 to line 17 during said fifth inspection period; that sector-controlling roller 156, which has traveled in the long straight part *e* of cam-groove 157 from line 0 to line 17, now actuates said sector by entering incline *d* between lines 17 and 18, thus turning the carrier 99 from the position shown in Fig. 14 to 55 the point-inspecting and discharging position, (illustrated in Figs. 15 and 29;) that the cam travels from line 18 to line 19 during the sixth inspection period, the rollers 163 and 167' being then in engagement with the straight parts *i* and *s* of cams 164 170; that at the conclusion of this inspection period the circuit is broken as roller 148 travels along inclined part 149' and flat part 149³ between lines 19 and 21; that said circuit is reestablished when the roller 148 travels down incline 149² of cam 149 and is continued while the roller is in contact with the main straight part of said cam; that the sector is actuated to turn the carrier to its nail-receiving position as roller 156 travels 60 from line 20 to line 22 in incline *f*; that the carrier and its arms are rocked to the position represented in Fig. 26 to receive a new lot of nails when the roller 126 travels along incline 128 of groove 127 from line 22 to line 23; that 65 rollers 126 156 simultaneously travel along incline *g* of cam-groove 157 and incline 128 of cam-groove 127 to move the sector 151, shaft 121, and carrier-arms 113 113' in unison as the cam travels from line 22 to line 23 to bring 70 the carrier to the nail-receiving position shown in Fig. 26, and that said sector and arms are simultaneously raised to the head-inspecting position (represented in Figs. 10 and 27) when rollers 126 and 156, respectively, enter the inclines *h* and 129 of grooves 157 and 127 as the cam travels from line 23 to line 24, when the operations just described will be repeated as long as the machine is in operation. During 75 all of these operations nails are being discharged from the continuously-vibrated hopper 34 into the pockets 57 of drum-wheel 54, and should a nail be deposited in a wrong position in any of said pockets or be of such dimensions that it cannot enter the passage 58 80 between each pair of diamond-shaped cross-

bars 56 it will drop by gravity from such pocket when the drum-wheel is intermittently rotated to the required position by the means described. As the drum-wheel is intermittently rotated the screw conveyers 93 94 are 70 also intermittently actuated, and consequently the nails fall one by one from the feed-rolls 69 70 into the chute 89, drop on edge through said chute, and enter the spaces between the threads of said screw conveyers while the latter are stationary, as shown in Fig. 18, and are advanced by the conveyers until a column of the desired number is formed, to be received into the notches 100' of the carrier in the manner above described. 80

It may happen that during some one of the six inspection periods it is desirable to stop the machine suddenly to afford more time for inspection or to remove the nails if an imperfect lot is held by the carrier, and in this connection it is important that the selecting and feeding devices should continue in operation as long as possible, so that a full supply will always be ready for the carrier. To enable this result to be accomplished, the wheel 176 90 is provided on shaft 32, and this wheel, as before stated, has a number of teeth or projections 1, 2, 3, 4, 5, and 6, teeth 1 and 5 being of the same width, teeth 2, 3, and 4 of the same width, and tooth 6 of much greater 95 width than any of the others. Between each pair of teeth is what may be termed an "inspection-space," and when the by-pass 181 is opposite any of said inspection-spaces and it is desired to stop the machine this can be 100 done by depressing treadle 22 and, through link 24 and angle-lever 19, shifting clutch-sleeve 14 to the right, (see Fig. 4,) and thus disengaging clutch-surfaces 15 and 17. Should, however, an attempt be made to stop 105 the machine between two inspection periods, the by-pass 181 will engage one of the teeth of wheel 176 and prevent such action, the lost motion of the link 24, due to slot 24', permitting, however, a movement of the treadle 110 when depressed without shifting the angle-lever and clutch-sleeve until the by-pass engages one of the teeth. Should one of the teeth of the wheel engage the by-pass as said wheel rotates in the direction of the arrow in 115 Fig. 2, said by-pass will be rocked on its pivot and will after the tooth passes be immediately returned to normal position by the spring 183.

My invention is not limited to the precise 120 devices shown and described nor to the arrangement and proportions of parts illustrated, for many changes may be made without departure therefrom. Furthermore, the nails may be fed to a position for reception 125 by the carrier by various means different from those shown, and other mechanism may be employed for actuating the carrier without departure from the invention. So, too, the carrier may be constructed to receive one 130

or any number of nails and the means for holding and turning the nails may be different from those shown, the invention not being limited in this respect.

5 Many of the parts of the machine—for instance, the nail selecting and feeding mechanism and the electromagnetic carrier—may also be employed in different relations and in different arts, if desired, without departure 10 from the field of the invention.

No claim is herein made to the magnetic carrier, for it will constitute the subject of a separate application.

Having thus described my invention, what 15 I claim is—

1. In an inspecting-machine, the combination, with a carrier for supporting an article, of means for turning said article while held by the carrier into a position for inspection.

20 2. In an inspecting-machine, the combination, with a carrier for supporting an article, of means for turning said article while held by the carrier into a plurality of positions for inspection.

25 3. In an inspecting-machine, the combination, with a carrier, of means for supplying an article to said carrier; means for actuating the carrier; and means for turning the article while supported by the carrier into a position 30 for inspection.

35 4. The combination, with a nail-supporting carrier, of feed mechanism for supplying the carrier; and means for turning the product held by said carrier into various inspection positions.

40 5. The combination, with a nail-supporting carrier, of means for turning the product while held by the carrier into a plurality of positions for inspection; and means for actuating the carrier to a position for the final inspection and discharge of said product.

45 6. In an inspecting-machine, the combination, with feed mechanism, of a carrier; means for actuating the carrier; and means for turning the product held by said carrier into a plurality of positions for inspection purposes.

50 7. In an inspecting-machine, the combination, with selecting and feed mechanism, of a carrier for receiving an article from the feed mechanism; and means for turning said article into a plurality of positions for inspection purposes.

55 8. In a machine of the class described, the combination, of the following instrumentalities or organisms: feed mechanism; a carrier; means for turning the product held by the carrier; and means for actuating said carrier to different positions.

60 9. In a machine of the class described, the combination, with feed mechanism, of selecting mechanism; a carrier; mechanism for delivering the selected product to said carrier; means for actuating the carrier; and means for turning the product held by the carrier

into a plurality of positions for inspection purposes. 65

10. In an inspecting-machine, the combination, with a selecting device, of a carrier; means for conveying the product from the selecting device to said carrier; means for actuating the carrier; and means for turning the product while held by the carrier into a plurality of positions for inspection purposes. 70

11. The combination, with a device having pockets for the reception of articles and passages leading from said pockets, of means for rotating said device; mechanism for receiving and feeding the articles delivered from the passages; conveying mechanism for receiving the articles delivered by the feeding mechanism; a carrier; means for actuating the carrier toward and from the conveying mechanism; means on the carrier for holding the articles; and means for turning the articles while they are held by said carrier. 80

12. A selecting device having pockets for the reception of articles, and discharge-passages of area sufficient to receive articles of standard size leading from the pockets, whereby articles of oversize will not be admitted to 90 said passages, combined with means for actuating said device to bring the pockets into receiving position.

13. A selecting device having individual flaring pockets and passages for admission of 95 articles of standard size leading from said pockets, whereby articles of oversize will be rejected, combined with means for actuating said selecting device to bring the pockets into receiving position. 100

14. A nail selecting and delivering device having pockets, and passages adapted to receive articles of standard size, and to reject those of oversize, leading from said pockets, combined with mechanism for actuating said 105 device to bring the pockets into position for the reception of nails; and mechanism for receiving and feeding the product delivered by said device.

15. The combination, with a hopper, and with means for agitating the same, of a selecting device having pockets, and passages adapted to receive articles of standard size, and to reject those of oversize, leading from said 115 pockets; means for actuating said selecting device; feed mechanism; conveyer mechanism; a chute connecting said feed and conveyer mechanisms; a carrier; and means for actuating the carrier toward and from the conveyer mechanism. 120

16. A nail-selecting wheel having a series of flaring pockets, and a series of passages leading from said pockets, each passage being of area sufficient to receive a standard size of nail, but to reject a nail of oversize; combined with means for actuating said selecting-wheel. 125

17. A nail-selecting wheel having a tubular hub, pockets, and radial passages, each of area

- sufficient to receive a nail of standard size, leading from said pockets through the hub.
18. The combination, with a hopper, and with means for vibrating the same, of a selecting-wheel having flaring pockets, a tubular hub, and passages, each of area sufficient to receive a nail of standard size, leading from said pockets through the hub; means for intermittently rotating said wheel; and means for conveying the selected nails away from said wheel.
19. The combination, with a vibrating hopper, of a selecting-wheel having pockets and passages, each of area sufficient to receive an article of standard size, but to reject an article of oversize, leading from said pockets; means for intermittently rotating said wheel; and means for receiving and delivering the product accepted by said wheel.
20. A nail-selecting wheel composed of end plates, a tubular hub, and tubular, diamond-shaped cross-bars connecting said end plates and hub.
21. The combination, with feed mechanism, of a chute into which the articles delivered by said feed mechanism are discharged; conveyer mechanism for receiving the articles from the chute; a carrier; means on the carrier for holding the article; means for actuating the carrier toward and from said conveyer mechanism; and means for rotating said articles on the carrier to present them for inspection.
22. The combination, with rotary feed-rolls, of a chute; conveyer-screws for receiving the product delivered by said chute; a carrier; means on the carrier for holding the product to be inspected; means for actuating the carrier toward and from the conveyer-screws; and means for intermittently rotating the product on the carrier to present it for inspection.
23. The combination, with rotary feed-rolls, one of which has a threaded portion, of a chute into which the product is delivered by said feed-rolls; conveyer-screws for receiving the product from the chute; a carrier; means on the carrier for taking the product from the conveyer-screws; means for actuating the carrier toward and from said conveyer-screws; and means for turning the product on the carrier to present it for inspection.
24. The combination, with a pair of rotary feed-rolls, of a chute having a slot in one of its walls; a pair of conveyer-screws; means for actuating said screws; a carrier; and means for actuating the carrier toward and from the conveyer-screws.
25. The combination with feed mechanism, of a chute located at an angle to said feed mechanism, and having a slot of a width to receive a shank of a nail when delivered by said feed mechanism, the slot being of dimensions to prevent the passage of the head of the nail.
26. The combination, with inclined feed-rolls, and with means for rotating the same,
- of a chute located at an angle to said feed-rolls, and having a slot in one of its walls through which the shank of a nail may pass as it is delivered by the feed-rolls, said slot being of a width to prevent the passage of the head of the nail, should it turn as it leaves the feed-rolls.
27. The combination, with a hopper, and with means for vibrating the same, of a rotary wheel having pockets and passages leading from said pockets; feed-rolls for receiving the product delivered from the passages; means for actuating said feed-rolls; a chute located at an angle to the feed-rolls, and having a slot in one of its walls; screw conveyers; and means for actuating said screw conveyers.
28. The combination, with a hopper, and with means for vibrating the same, of a drum-wheel having pockets, passages leading from said pockets, and a tubular hub; inclined feed-rolls passing through the hub of the drum-wheel; means for rotating said rolls; a chute located at the delivery end of the feed-rolls; screw conveyers; means for actuating said screw conveyers; a carrier; and means for actuating said carrier toward and from the screw conveyers.
29. The combination, with a feed device, and with means for actuating the same, of a carrier; means on the carrier for holding the product delivered from the feed device; means for actuating one of said devices toward and from the other; and means for intermittently rotating the product to present it for inspection.
30. In an inspecting-machine, a carrier for presenting an article for inspection, combined with a device for engaging the article and turning it while held by the carrier; and means for actuating said device.
31. In an inspecting-machine, a carrier having means for holding articles, combined with means for turning said articles; and means for moving the carrier from one inspecting position to another inspecting position.
32. In an inspecting-machine, a carrier having an article-holding device, combined with means for turning the article; means for actuating the carrier; and means for supplying the article to said carrier.
33. A magnetic carrier, combined with means for turning an article held thereon.
34. A carrier having an electromagnet, combined with a circuit; means for making and breaking said circuit; and means for turning the article for inspection while held on the carrier by the electromagnet.
35. In combination, with feed mechanism a carrier; means on said carrier for holding one or more nails; means for turning the product held by the carrier into a plurality of positions for inspection; and means for actuating the carrier from one position to another position, and for holding it stationary during the inspection period.

36. In combination, with a carrier; means on said carrier for holding one or more articles; means for turning the product held by the carrier for inspection; and means for rocking the carrier from one position to another position. 65
37. In an inspecting-machine, in combination, a carrier, and means carried thereby for holding one or more articles; means for turning the product held by the carrier into a plurality of positions for inspection; and means for actuating the carrier to positions to receive and then to discharge said product. 70
38. In combination, a carrier, and means thereon for holding one or more articles; means for turning the product held on the carrier into a plurality of positions for inspection; means for actuating the carrier to a product-receiving position and to a product-inspection position; means for rocking the carrier to a product-discharging position; and means for rocking the carrier intermediate said positions and for holding it at rest during the inspection periods. 75
39. In combination, with a carrier and an electromagnet thereon for holding one or more articles, means for turning the product held on the carrier into a plurality of positions for inspection; means for rocking the carrier to a discharge position; a circuit; and means for making and breaking said circuit. 80
40. In combination, a carrier, electromagnets on the carrier; a circuit; means for making and breaking said circuit; means for turning the product on the carrier; means for rocking the carrier; and means for preventing the effect of residual magnetism when the carrier is rocked to a discharging position and the circuit is broken. 85
41. In an inspecting-machine, in combination, a shaft; means for rocking said shaft; arms secured to the shaft, and having bearings; a carrier for the product to be inspected, and having trunnions journaled in the bearings of the arms; and means for axially rotating the carrier. 90
42. In an inspecting-machine, in combination, a shaft; means for rocking said shaft; arms secured to the shaft, and having bearings; a magnetic carrier for the product to be inspected, and having trunnions journaled in and insulated from said arms; a circuit; means for making and breaking said circuit; and means acting upon one of the trunnions for rotating the carrier. 95
43. In an inspecting-machine, in combination, a carrier for the product to be inspected; feed mechanism; cam-controlled mechanism for actuating the carrier toward and from said feed mechanism; and gearing for axially rotating the carrier. 100
44. In an inspecting-machine, in combination, a carrier for the product to be inspected; arms in which it is supported for swinging movement; means for axially rotating the carrier; and means for actuating the arms. 105
45. In an inspecting-machine, in combination, a shaft; arms secured to said shaft; cam-controlled mechanism for rocking the shaft; a carrier for the product to be inspected, and having trunnions journaled in the arms; a gear carried by one of the trunnions; a sector in engagement with said gear; and means for actuating said sector. 110
46. In combination, a shaft having a crank-arm to which power is applied; a pair of separated arms rigid with said shaft; a carrier journaled in said arms; a pinion secured to the carrier; and means for partially rotating said pinion at intervals. 115
47. In combination, a shaft journaled in bearings of the frame; a crank-arm rigid with the shaft; mechanism for actuating said crank-arm; a pair of arms rigid with the shaft; a carrier having trunnions journaled in said pair of arms; a pivoted sector in mesh with the pinion; and means for intermittently actuating the sector. 120
48. In combination, a shaft; means for rocking the shaft; arms rigid with said shaft; a carrier having electromagnets; an electric circuit, means for making and breaking the circuit; feed mechanism; means for turning the articles held by the carrier; and means for axially rocking the carrier at intervals. 125
49. In a nail-inspecting machine, the combination, with feed mechanism, of a nail-receiving carrier; a main cam-drum; cam-controlled mechanism for actuating said carrier toward and from the feed mechanism; and cam-controlled mechanism for intermittently rocking the carrier from one position to another. 130
50. In a nail-inspecting machine, the combination, with conveyer-screws, of a chute for delivering nails to said screws; a device for retarding the passage of each nail as it falls from the chute upon said conveyers; and an abutment for receiving the impact of the nails as they are delivered to the conveyer-screws. 135
51. In combination, a supply-chute, a spring for retarding the speed of a nail as it leaves said chute; feed mechanism into which the nails pass as they leave the chute; and a device for receiving the impact of the nail as it is delivered to the feed mechanism. 140
52. In combination, a supply-chute; a spring bearing upon, and retarding the speed of, the nail as it leaves the chute; an abutment for receiving the impact of the nail delivered by the chute; screw conveyers to which nails are also delivered by the chute; and means for actuating said screw conveyers. 145
53. In combination, screw conveyers; means for actuating said conveyers in the same direction; and means bearing against the ends of the articles and for preventing them from rising between the threads of said screw conveyers. 150

54. In combination, screw conveyers; means for intermittently rotating said screw conveyers in the same direction; a nail-delivery chute; means for retarding the speed of the nail as it leaves said chute and enters between convolutions of said conveyers; and an abutment-plate having a flange for preventing displacement of the nail as it is fed along by said screw conveyers.
55. In combination, screw conveyers; gears on the shafts of said conveyers; a gear in engagement with said gears; means for rotating said gear, and thereby the screw conveyers, in the same direction; and a device bearing against the end of the product advanced by the conveyers, and thereby preventing its displacement from between the threads of said screw conveyers.
56. The combination, with a nail-retaining carrier, of a chuck for engaging a nail held by said carrier; means for reciprocating said chuck toward and from the carrier; and means for rotating the chuck to turn the nail for inspection.
57. The combination, with a nail-holding carrier, of means for engaging the nails and imparting quarter-turns to them while held by said carrier.
58. The combination, with a nail-holding carrier, of chucks for advancing and engaging the nails while held by said carrier; means for imparting a quarter-turn to the chucks; a slide in which the chuck-spindles are journaled; and means for reciprocating the slide.
59. The combination, with a nail-supporting carrier, of a chuck for engaging and rotating the nail while held on said carrier, said chuck having a nail-receiving slot, and back of said slot a chamber to permit slight wabbling movement of the nail; means for reciprocating the chuck; and means for rotating the chuck.
60. The combination, with a nail-supporting carrier, of a slide; means for advancing and retracting said slide; spindles journaled in the slide; pinions on said spindles; a rack movable on the slide and in mesh with said pinions; and chucks, adapted to engage and turn the nails, rigid with the spindles.
61. The combination, with a nail-supporting carrier, of a chuck having a flared end, a slot for the reception of the nail-shank, and back of said slot a chamber; means for reciprocating said chuck; and means for rotating the chuck.
62. The combination, with a nail-supporting carrier, of a slide; a series of chuck-spindles journaled in the slide; chucks for engaging the nails carried by the spindles; cam-controlled mechanism for actuating the slide; a rack carried by the slide; pinions carried by the chuck-spindles, and in engagement with the rack; an angle-lever for reciprocating the rack; a cam for actuating the angle-lever; and a spring for returning said angle-lever.
63. The combination, with a nail-holding carrier, of a slide; chuck-spindles journaled in the slide; pinions on the chuck-spindles; a pinion-engaging rack movable in a groove of the slide, and having a slotted head; an angle-lever having a pin fitted in the slot of said head; means for actuating the angle-lever; and means for actuating the slide.
64. The combination, with a carrier having seats for nails, of an abutment; chucks for engaging the nails and forcing them against said abutment; means for reciprocating the chucks; and means for rotating said chucks.
65. The combination, with a carrier having seats for nails, of chucks for engaging the shanks of said nails; means for reciprocating the chucks; means for rotating said chucks; and an abutment-bar against which the heads of the nails are forced when the chucks engage the nail-shanks.
66. The combination, with a hopper, of a shaft having a head connected thereto; a sleeve surrounding said shaft; a bearing in which said sleeve is secured; an antifriction-washer between the end of the sleeve and the head of said shaft; an arm secured to the shaft; and means for actuating the arm to cause it to vibrate the shaft and hopper.
67. The combination, with a shaft having a forked head, of a hopper pivoted and angularly adjustable between the arms of said forked head; an antifriction-washer; a sleeve; a bearing in which said sleeve is adjustable; an arm secured to the shaft; an undulatory cam for actuating the arm in one direction; and a spring for actuating said arm in an opposite direction.
68. In combination, a carrier; electromagnets carried by said carrier; a coil; an electric circuit; contact-strips; a cam; a lever; and a contact-rod carried by, and insulated from said lever, and adapted to engage and disengage the contact-strips, to make and break the circuit.
69. In combination, a carrier; electromagnets on said carrier; an energizing-coil; a circuit; contact-strips; an angle-lever; a contact-rod carried by, and insulated from, said angle-lever and projecting between the contact-strips; a cam for actuating said angle-lever in one direction; and a spring for actuating said lever in an opposite direction, whereby said contact-rod is thrown into engagement with, and out of engagement from, said contact-strips, to make and break the circuit.
70. In combination, a hollow carrier having trunnions; supports having bearings in which said trunnions are mounted; spools of insulating material surrounding the trunnions in said bearings; contact-rings on the spools; a coil within the carrier, and having its terminals in engagement with said contact-rings; electromagnets on the carrier; contact-strips insulated from the frame; contact-strips secured to and insulated from, the bearing-sup-

ports, and in engagement with the contact-rings of the carrier and the contact-strips of the frame; an electric circuit; and means for making and breaking said circuit.

5 71. The combination, with a carrier, and with swinging supports for the same, of electromagnets on the carrier; a coil on the carrier; contacts insulated from the carrier, and connected with the coil; contacts insulated 10 from the frame; contact-strips insulated from, and carried by, the swinging supports; an electric circuit; means for making and breaking said circuit; and means for intermittently rotating the carrier.

15 72. The combination, with screw conveyers, of means for delivering nails thereto; means for intermittently rotating said conveyers after they have received a nail, and for holding them stationary for the reception 20 of another nail; an electromagnetic carrier; means for actuating the carrier toward and from the screw conveyers; and means for rotating the nails intermittently to present them for inspection while held on the carrier.

25 73. The combination, with screw conveyers, of a chute for delivering nails to said screw conveyers; means for rotating said conveyers after the reception of a nail, and for holding them stationary to receive a following nail; a carrier; means on the carrier for taking the nails from said conveyers; means for actuating said carrier toward and from the screw conveyers; and chucks for rotating the nails intermittently to present them for inspection while held on the carrier.

35 74. The combination, with a carrier for holding nails, of a shaft; means, including a clutch, for driving said shaft; means controlled by the shaft for actuating said carrier 40 to present the nails in different positions for inspection; and means for shifting the clutch.

75. The combination, with a carrier, of means on the carrier for holding and releasing the nails; a shaft; means, including a clutch, 45 for driving said shaft; a cylinder carried by the shaft, and having a series of cams; means controlled by said cams for actuating the carrier to different positions to present the nails for inspection; and means for turning the 50 nails while held on the carrier.

76. The combination, with a carrier, of means on the carrier for holding and releasing nails; feed mechanism; a shaft; means, including a clutch for driving said shaft; a cylinder carried by the shaft, and having a series 55 of cams; means controlled by certain of said cams for actuating the carrier toward and from the feed mechanism; and means controlled by other cams of said cylinder for rotating the nails on the carrier to different inspecting positions.

77. In a nail-inspecting machine, the combination, with a carrier on which the nails are placed and held for inspection, of cam-controlled 60 mechanism for actuating said carrier;

and cam-controlled mechanism for turning the nails to different inspecting positions.

78. In a nail-inspecting machine, the combination, with a carrier upon which the nails are placed and held for inspection, of mechanism 70 for actuating said carrier; mechanism for turning the nails to different inspecting positions while held on the carrier; means, including a clutch, for actuating said mechanisms; and means for preventing stoppage of 75 the machine except during one of the nail-inspecting periods.

79. The combination, with a carrier upon which nails are placed for inspection, of a main cam-cylinder; feed mechanism; means 80 controlled by certain cams of said cylinder for actuating the carrier toward and from the feed mechanisms; means controlled by other cams of the cylinder for intermittently rotating the carrier; means controlled by other 85 cams of said cylinder for turning the nails to different inspecting positions while held on the carrier; means, including a clutch, for driving the cam-cylinder; and means for preventing the shifting of said clutch to stop the 90 machine, except during one of the nail-inspecting periods.

80. The combination, with a carrier, and with means thereon for holding and releasing nails, of feed mechanism; means for actuating 95 said carrier toward and from the feed mechanism; a cam-cylinder constituting a part of said means; means actuated by cams of said cylinder for turning the nails to different inspecting positions while held on the carrier; a shaft; 100 a clutch on said shaft; means carried by the shaft for driving said cylinder; means for normally shifting the clutch into an operative position; and means for preventing the shifting of said clutch to an inoperative position 105 except during one of the nail-inspecting periods.

81. In a nail-inspecting machine, the combination, with a main cam-cylinder, of a shaft on which said cylinder is mounted; a toothed 110 wheel on the shaft; gearing for driving said shaft; a shaft for actuating said gearing; a clutch on said shaft, said clutch being normally in position to engage an element for driving the shaft; a treadle; and means controlled by the treadle for shifting the clutch 115 when one of the spaces between the teeth of said toothed wheel is in position to permit of such action.

82. The combination, with a driving-shaft, 120 of a clutch-sleeve rotary with, and movable on, said shaft; a lever connected to said clutch-sleeve, and having a pin; a clutch; a driving element having a clutch-surface; a link having a slot fitted over said pin; means for actuating said link; a lever connected to the link-actuating means; a spring for normally actuating said lever to throw the clutch into engagement with the clutch-surface of the driving element; a gear on the driving-shaft; cam 125 130

mechanism actuated by said gear; a carrier actuated by said cam mechanism; and a device for preventing the shifting of the clutch, to stop the machine, except at predetermined 5 times.

83. The combination, with a carrier for holding and presenting nails for inspection, of means for actuating said carrier; means for turning the nails to different inspection positions while held on the carrier; and means for preventing the stoppage of the machine except during any one of the nail-inspecting periods.

84. In a nail-inspecting machine, the combination, with feed mechanism, of a carrier; devices on said carrier for holding a nail or nails; means for actuating the carrier toward and from the feed mechanism; mechanism for intermittently rotating the carrier; and means 20 for preventing the action of the carrier-rotating mechanism during the movements of the carrier toward and from the feed mechanism.

85. The combination, with a nail-holding carrier, of arms in which said carrier is journaled; feed mechanism; means for swinging the arms toward and from said feed mechanism; a pinion on the carrier; a rocking sector in engagement with the pinion; means for actuating said sector to turn the carrier; and 30 means for preventing said sector from turning the pinion when the carrier is swung toward and away from the feed mechanism.

86. The combination, with an intermittently-rotatable carrier having trunnions, of means 35 for holding nails on said carrier; means for intermittently rotating the nails to present them for inspection; supports in which the trunnions are journaled; and means carried by one of said supports, and engaging one of the trunnions, for holding the carrier when turned.

87. The combination, with supports having bearings, of a rotatable carrier having trunnions journaled in said bearings, one of said trunnions having locking-surfaces; a spring-45 actuated plunger carried by one of the supports, and adapted to engage said locking-surfaces when the carrier is rotated; and means for intermittently rotating articles held by the carrier to present them for inspection.

50 88. In an inspecting-machine, the combination, with a selecting-wheel having pockets, and passages leading from said pockets; of feed-rollers arranged to receive the articles delivered by the passages; means for actuating said feed-rollers; a chute; screw conveyers; and means for simultaneously and intermittently actuating the pocket-wheel and said conveyers.

89. In an inspecting-machine, the combination, with a hopper, and with means for vibrating the same, of a pocket-wheel; screw conveyers; means for conveying the articles delivered from the pockets of the wheel to said screw conveyers; and means for synchronously

actuating said pocket-wheel and said screw conveyers.

90. The combination, with a pocket-wheel having passages leading from the pockets and a tubular hub, of means for delivering articles to said wheel; a ratchet-wheel rigid with the hub of said pocket-wheel; feed-rollers passing through the hub of said pocket-wheel; a pivoted lever carrying a pawl adapted to engage the ratchet-wheel; and means for actuating said lever.

75 91. The combination, with a pocket-wheel having a tubular hub, and passages leading from the pockets of said wheel through the hub, of a ratchet-wheel rigid with said hub; a pivoted lever carrying a pawl in engagement with the teeth of said ratchet-wheel; means for actuating said lever; inclined feed-rollers passing through said hub; means for rotating said feed-rollers; a chute at the delivery end of the feed-rollers; screw conveyers for receiving the product passing through the chute; and means for intermittently actuating said screw conveyers.

80 92. In a machine for selecting and inspecting horseshoe-nails, the combination, with delivery and feed mechanism, of a carrier; means carried by said carrier for holding the nails; means for turning the nails to different inspection positions while held on the carrier; a driving-shaft; mechanism, including a clutch, 95 for rotating said shaft; a cam-cylinder driven by the driving-shaft; means operated by cams of said cylinder for actuating the carrier; means actuated by other cams of said cylinder for turning the nails on the carrier; a stop-wheel; and means controlled by said wheel for preventing the shifting of the clutch, except during any one of the nail-inspection periods.

90 93. In a machine, of the class described, the combination, with a cylinder having a series 100 of cams, of a carrier; means for holding and discharging nails carried by said carrier; feed mechanism; means operated by certain cams of the cylinder for actuating the carrier toward and from said feed mechanism; means controlled by other cams of the cylinder for turning the nails to different inspection positions upon the carrier; a worm-wheel on the cylinder-shaft; a driving-shaft having a worm 105 in engagement with said worm-wheel; means, including a clutch, for actuating the driving-shaft; means for shifting said clutch; and means for preventing the clutch-shifting operation except during the nail-inspection 110 periods.

In testimony whereof I affix my signature in presence of two witnesses.

CHARLES W. SPONSEL.
